UNITED STATES PATENT OFFICE

2,327,653

PNEUMATIC CARTRIDGE AND GUN

Elmer Lisle, Milwaukee, Wis.

Application April 23, 1941, Serial No. 389,995

1 Claim. (Cl. 124—11)

This invention relates to weapons such as pistols, revolvers, rifles and other guns wherein compressed air or other gas is used as a propulsive medium for a projectile.

More particularly the invention relates to a compressed air cartridge for such weapons.

In weapons of the general type known as "air guns" or "air pistols" it is common to provide a chamber permanently in or on some part of the weapon and so connected to the barrel that a charge of compressed air may be admitted behind the projectile to propel the latter from the barrel. The repetition of discharges from such a weapon makes it necessary to repeatedly recharge the compressed air chamber which is a time consuming operation.

The principal object of the present invention is to provide a novel compressed air cartridge for a weapon of this type which cartridge may be employed with the same facility in loading as the ordinary powder cartridge.

With the above and other objects in view, the invention consists in general of certain novel details of construction and combinations of parts hereinafter fully described, illustrated in the accompanying drawing and pointed out in the appended claim.

In the accompanying drawing like characters of reference indicate like parts in the respective views, and;

Fig. 1 is a side elevation of the novel compressed air cartridge.

Fig. 2 is a front end view thereof on an enlarged scale.

Fig. 3 is an enlarged section on the line 3—3 of the cartridge, a portion of the gun in which this cartridge is used being also shown in section.

Fig. 4 is a perspective view of a valve seat sleeve forming part of the cartridge.

Fig. 5 is a perspective view of the valve used in this cartridge.

Fig. 6 is a longitudinal sectional view of a modified form of the cartridge.

In the embodiment of the invention shown in the present drawing the weapon parts are indicated in general at 5. This weapon includes a barrel 6 having at its rear end a cartridge chamber 7. A breech closure 8 is arranged at the rear of the barrel and is movable into and out of breech closing position, the means for so actuating the breech closure not being here shown as they form no part of the present invention. The breech closure or block is here shown as provided with a plunger 9 in axial

alignment with the cartridge chamber when the breech is closed. The purpose of this plunger will be presently explained but the operating means therefor are not shown as the specific means which may be employed forms no part of the present invention.

It will be seen from Fig. 3 that the cartridge chamber 7 is of considerably greater diameter than the bore 10 of the weapon and that the bore 10 is carried back into the chamber 7 through a boss 11 so that an annular recess 12 is provided at the forward end of the chamber 7.

The cartridge has a tubular body 13 of proper diameter to fit snugly in the chamber 7. This body has a rear end closure 14 formed integrally with the body and, at its forward open end, is internally threaded as at 15. In the forward end of the body 13 is fitted a valve seat member having a tubular body 16 externally threaded to screw into the threaded part 15. On the forward end of the body 16 is provided a flange 17 of the same diameter as the body 13. At its rear part this member has a bore 18 terminating rearwardly in a bevelled valve seat 19. At its forward end the bore 18 opens into an enlarged bore 20 of such diameter as to receive the boss 11 so that the forward end of the assembled body 13 and valve seat member may slide into the recess 12. Slidable in the bore 18 is a valve member which has a body 21 fitting in the bore 18 and which is provided at its rear end with a head 22 having a bevelled face 23 normally seated on the seat 19. This valve member has a bore 24 extending from its forward end, the head 22 closing the rear end of this bore. The forward end of the bore 24 is enlarged to substantially the same diameter as the bore 10, an abrupt shoulder being formed at the rear end of said enlarged portion to constitute a seat for the base of a projectile P. Ports 25 are formed in the sides of the valve just forward of the head 22. A stop stem or member 26 projects rearwardly from the valve member to limit movement of the valve with respect to the outer member of the cartridge and a spring 27 urges the valve against its seat.

In preparation for use a suitable pipe fitting (not shown) is applied to the valve member so as to push the valve rearwardly and open the ports 25. Compressed air or gas is introduced through the fitting at the pressure desired after which the valve is allowed to close, the fitting is removed and the projectile seated in place.

In using the cartridge it is inserted in the cartridge chamber and the latter is closed by

the breech block. In firing the plunger 9 moves forward carrying the cartridge with it until the valve strikes the rear end of the boss whereupon the cartridge body moves forwardly to open the ports 25 and allow the compressed air to flow from the body of the cartridge to the bore 24 and thus to force the projectile out through the bore 10. Upon opening the breech after firing the usual ejector finger will engage the groove 28 and withdraw the cartridge which may be re-loaded.

Having thus described my invention what I claim and desire to protect by Letters Patent is:

The combination of a gun having a cartridge receiving chamber, an annular boss formed on the inner end of the barrel of the gun and extending into the cartridge chamber with a bore therein aligning with the bore of the gun, said

boss being of lesser diameter than that of the cartridge chamber, a compressed air cartridge having an enlarged bore in its forward end disposed in the cartridge chamber with its bore disposed rearwardly of the boss of the gun and in alignment therewith when in normal position, a spring closed valve in the forward end of the cartridge and having a projectile receiving bore communicating with the compressed air chamber of the cartridge, said valve having its forward end extending into the bore thereof in close opposed relation to the boss of the gun, and means carried by the gun to simultaneously force the cartridge toward the barrel of the gun and open the valve by pressing it against the boss of the gun to eject a projectile retained by the valve in alignment with the bore of the gun.

ELMER LISLE.
